(57) **CLAIM**

The ornamental design for a container for measuring electrical characteristics, as shown and described.

DESCRIPTION

FIG. 1 is a perspective view of a container for measuring electrical characteristics showing our new design;

FIG. 2 is a left side elevational view thereof;

FIG. 3 is a cross sectional view along the line 3-3 of FIG. 2; and,

FIG. 4 is a right side elevational view thereof.

The even-dash broken lines showing of unclaimed portions of the container for measuring electrical characteristics and form no part of the claimed design. The dot-dash broken lines define the boundaries of, but not included in, the claimed design.

1 Claim, 2 Drawing Sheets
